UNITED STATES PATENT OFFICE.

WALTER A. FLOWERS, OF RIVERSIDE, TENNESSEE.

TIE-LOADING MACHINE.

1,212,617.

Specification of Letters Patent. Patented Jan. 16, 1917.

Application filed April 1, 1916. Serial No. 88,351.

To all whom it may concern:

Be it known that I, WALTER A. FLOWERS, a citizen of the United States, residing at Riverside, in the county of Lewis and State of Tennessee, have invented certain new and useful Improvements in Tie-Loading Machines, of which the following is a specification.

My invention relates to new and useful 10 improvements in tie loading machines, the primary object of my invention being the provision of a power driven mechanism for loading cross ties upon coal cars.

A further object of my invention consists 15 in providing a mechanism of the above described type in which the ties are drawn upwardly along an inclined skidway, one end of which detachably engages the wall of the coal car and the other end of which rests 20 upon the ground or other suitable support placed thereon, the ties being drawn along the skidway by an endless conveyer driven by an internal combustion engine or other suitable source of power.

A still further object of my invention is 25 to provide a hanging support for the internal combustion engine and drive gears thereof which may be detachably secured to the wall of the car in order that the engine may, under all circumstances, be located at a pre- 30 determined point with respect to the drive shaft of the conveyer chain, irrespective of the inclination of the skidway.

A still further object of my invention con- 35 sists in bracing the skidway and in providing the upper face of the frame or skid members with grooves or channels to seat the stretches of the conveyer chain in order that the wear of the moving ties shall be 40 taken up by the skidway itself and not by the chains.

With these and other objects in view, my 45 invention will be more fully described, illustrated in the accompanying drawings, and then specifically pointed out in the claims which are attached to and form a part of this application.

In the drawings, Figure 1 is a side elevation of my improved tie loading machine in 50 operation, a portion of a conventional coal car being shown in transverse section; Fig. 2 is a top plan view of the mechanism shown in Fig. 1; Fig. 3 is a front elevation of the mechanism; Fig. 4 is a fragmentary per- 55 spective view, showing the means for trans-

mitting power from the internal combustion engine to the drive shaft of the conveyer mechanism; Fig. 5 is an enlarged transverse sectional view through one of the skids or frame members of the skidway, showing the 60 protective strip of metal covering the upper face of the skidway and also the groove or channel in which one of the conveyer chains seats. Fig. 6 is a fragmentary sectional view, illustrating certain details of construction. 65

Corresponding and like parts are referred to in the following description and indicated in all the views of the drawings by the same reference characters. 70

My improved tie loading machine consists essentially of a skidway, indicated as a whole by the numeral 10 and supporting an endless conveyer mechanism 11 and in a hanging support 12 for an internal combustion engine 13 which serves to drive the conveyer mechanism. For the sake of clearness, I have illustrated my invention in connection with a conventional coal car having a bottom or platform 14 and side walls 15. 80

The skidway 10 includes spaced parallel side frame members or skids 16, preferably formed of wood and of any desired length. These side members 16 are held in proper spaced relation at suitable intervals by transverse brace bars 17 and are held against spreading movement by tie bolts 18 having clamping nuts 19, the tie bolts being preferably disposed immediately adjacent the braces 17 in order to avoid any possible 90 springing or bowing of the side members toward or away from each other, due to the tightening of the tie bolts. The side members of the skidway may be additionally braced, if desired, by diagonal braces 20. 95

Secured against the lower faces of the side members of the skidway at their upper and lower ends are supporting blocks 21 and 22, respectively, the former of which are adapted to rest against the upper edge 100 of a car wall when the skidway is in use and the latter to rest upon either the ground or a suitable support, such as a tie 23. These blocks are secured to the side members by bolts 24 or other suitable fastening means 105 and certain of these bolts pass through eyes 25 formed in the outer ends of rods 26, these ends of the rods being seated in recesses formed in the inner faces of the blocks. The free ends of these rods are threaded to en- 110

gage and coöperate with the yoke of a turn buckle device 27, their intermediate portions passing through the sleeves 28 of spacer brackets 29 secured to the side members of the skidway, whereby the rods and turn buckles constitute trusses 30. The bolts 24, securing the blocks 21 to the side members of the skidway, also pass through lengths of strap metal 31, the intermediate portions 10 of which are looped downwardly, as shown, to provide stops 32 to engage the outer face of a car wall and the ends of which are down bent to provide hooks 33 engaging the inner face of the car wall. In use, the skidway 15 is supported in the manner shown in Fig. 1, the hooks and stops serving to hold the skidway in place, irrespective of its inclination to the ground.

Secured to the outer faces of the side 20 members of the skidways and in transverse alinement with each other are bearings 34 which journal transverse shafts 35 and 36. The shaft 35 carries sprocket wheels 37 which extend slightly peripherally above the 25 upper faces of the side members of the skidway, the side members being slotted, as shown at 38, to receive these sprocket wheels. In like manner, the shaft 36 carries similar sprocket wheels 39 which extend through 30 slots 40 formed in the side members of the skidway. The upper faces of the side members 16 are formed with longitudinal grooves 41 and wear strips 42, of metal, are secured to the side members 16 to form bearing surfaces 35 over which ties being loaded may pass, these strips being depressed longitudinally to fit within the grooves 41. Sprocket chains 43 are trained about the sprocket wheels 37 and 39 with their upper stretches 40 disposed within the grooves 41 of the side members 16 and these chains, at suitable distances, are provided with upstanding lugs 44 adapted to engage ties placed transversely of the skidway. It will, of course, be understood 45 that the lugs of one chain are transversely alined with the lugs of the other chain in order that the ties drawn along the skidway by the conveyer as a whole may be maintained in proper transverse position.

50 In connection with the above skidway, I employ a hanging bracket or platform 12 including arms 45 provided at their upper ends with hooks 46 to engage over the upper edge of the car wall 15 between the hooks 33 55 of the skidway. A floor or platform 47 is secured at its rear portion to the lower ends of these arms 45 and diagonal braces 48 connect the upper portions of the arms with the outer portion of the floor 47. Mounted upon 60 this floor or platform is the engine 13 having the crank shaft 49 which carries the usual fly wheel 50 and in addition the pinion 51. This pinion 51 meshes with a spur gear 52 fixed upon a shaft 53 journaled in 65 suitable bearings carried by the platform

and the shaft 53 carries a sprocket wheel 54. A drive chain 55 is trained about the sprocket wheel 54 and about a sprocket wheel 56 fixed upon the shaft 35. Preferably, some form of clutch mechanism, not shown, is interposed either between the shaft 53 and its gear 52 or between such shaft and its sprocket wheel 54.

From the foregoing description, taken in connection with the drawings, the operation 75 of my improved tie loading machine will be readily understood and no further explanation is necessary. It will be apparent, however, that various minor changes may be made, at any time, without in the slightest 80 degree departing from the spirit of my invention as set forth in the appended claims and I, therefore, reserve the right to make any changes which may seem advisable.

Having thus described the invention, what 85 is claimed as new is:

1. A machine of the character described including a skidway having means at one end for engagement with the side of a car, a supporting bracket having means for supporting engagement with the side of a car, an endless conveyer mounted upon the skidway, and means mounted upon the supporting member and operatively connected to the conveyer to drive the latter.

2. A machine of the character described including a skidway having parallel spaced side members, hooks secured to the members at one end for engagement with the side of a car to hold the skidway at an inclination to the ground, an endless chain conveyer mounted upon the skidway, means for driving the conveyer, and means for supporting the driving means from the side of the car in operative position with respect to the skidway.

3. A machine of the character described including a skidway having spaced side members formed in their upper faces with longitudinal channels, reinforcing strips extending along the upper faces of the side members and having instruck portions seating in the channels, an endless chain conveyer including conveyer chains having their upper stretches seating in the instruck portions of the reinforcing strips to lie flush with the outer faces of such strips, conveyer lugs extending from the chains, and means for driving the conveyer.

4. A machine of the character described including a skidway adapted to rest at one end upon the ground, hooks carried by the opposite end of the skidway for engagement with the upper edge of a car wall, an endless chain conveyer mechanism on the skidway including a drive shaft, a support having upwardly directed arms adapted to engage against the outer face of a car wall, hooks carried by the arms for engagement over the edge of the car wall, a prime mover 130

mounted upon the support, and driving means between the prime mover and drive shaft of the conveyer.

5. A machine of the character described including a skidway and a supporting platform adapted for independent detachable application to a car, an endless conveyer car-

ried by the skidway, a source of power carried by the platform, and operative connection between the source of power and conveyer. 10

In testimony whereof I affix my signature.

WALTER A. FLOWERS. [L.s.]
